UNITED STATES PATENT OFFICE.

ALBERT E. JOHNSON, OF NORTHFIELD, MINNESOTA.

PUMP.

1,165,261.

Specification of Letters Patent. Patented Dec. 21, 1915.

Application filed January 15, 1914. Serial No. 812,303.

To all whom it may concern:

Be it known that I, ALBERT E. JOHNSON, a citizen of the United States, residing at Northfield, in the county of Rice and State of Minnesota, have invented new and useful Improvements in Pumps, of which the following is a specification.

This invention is an improved pump for operation in deep wells, and consists in the 10 construction, combination and arrangement of devices hereinafter described and claimed.

The object of my invention is to provide an improved pump, all the operating parts of which are arranged at the upper end 15 above the mouth of the well, where they are readily accessible, and which pump operates to compress air and force it downwardly in the well casing and cause the compressed air to force up water from the 20 well casing through the delivery pipe of the pump.

In the accompanying drawings: Figure 1 is a vertical central sectional view of a 25 pump constructed in accordance with my invention. Fig. 2 is a similar view of the same on a plane at right angles to that of Fig. 1. Fig. 3 is a plan of the same. Fig. 4 is a horizontal sectional view of the same on the plane indicated by the line *a*—*a* of Fig. 1. Fig. 5 is a similar view on the plane indicated by the line *b*—*b* of Fig. 1. Fig. 6 is a 30 similar view on the plane indicated by the line *c*—*c* of Fig. 1.

In accordance with my invention, I provide 35 a cylinder 1 which is open at its lower end, and is adapted to be fitted on the upper end of the well casing 2, and to be secured to the well casing as by means of suitable screws or bolts 3. The said cylinder 40 has an internal shoulder 4 engaged by a gasket 5, the gasket fitting on the upper end of the well casing and effecting an airtight joint between the well casing and the lower portion of the cylinder, as will be 45 understood.

A piston 6 is arranged to operate vertically in the cylinder, and is here shown as comprising a pair of members 7, between which a packing leather or other element 8 50 is arranged, the said members being secured together by bolts 9, and the lower member being also provided with an annular packing 10 which operates in the cylinder. A shaft 11 passes transversely through the center of the cylinder, has its bearing therein, as at 12, and is provided with a crank 13

which is connected by a pitman 14 to the piston, the said pitman being pivotally connected to the piston, as at 15. At one end of the shaft is a gear 16 which engages a 60 smaller gear 17 on the drive shaft 18, the drive shaft being here shown as provided with a suitable power pulley 19. Any other suitable means may, however, be employed for operating the crank shaft and driving 65 the piston thereby, within the scope of my invention.

An air chamber 20 is arranged around the upper portion of the cylinder 4 and is provided at one side at its lower end with a 70 delivery pipe 21 which is here shown as provided with a spout.

A receiving pipe 22 is arranged in the well casing, extends downwardly therein to a point a suitable distance below the level 75 of the column of water or other liquid in the well casing, and is provided at its lower end with an upwardly opening valve 23 which constitutes the inlet valve. A discharge pipe 24 is arranged in and extends 80 through the receiving pipe, its lower end being open and arranged a slight distance above the bottom of the receiving pipe, and its upper end extending through the closed upper end of the receiving pipe and being 85 connected by a member 25 to the lower portion of the air chamber 20, from which the delivery pipe or spout 21 extends.

The head 26 of the cylinder is provided with a centrally arranged standard 29, the 90 lower portion of which forms a duct, and the upper portion of which has a spindle 30, on which a horizontally arranged ratchet wheel 31 is mounted for revolution. The said ratchet wheel is provided at points 95 at different distances from its center with tappets 32, 33 which project from the lower side thereof, and these tappets are arranged at opposite points of the ratchet wheel. A pipe 34 leads from the duct 29 to the receiving pipe 22, discharges into the upper end of the receiving pipe, and is provided at a point above the cylinder head and below the ratchet wheel 31 with an oscillating valve 35, which, when in one position, closes the 100 pipe 34, and when in another position, opens the same. This valve which is preferably a three-way valve has an arm 36 which projects from one side of its spindle. A pipe 37 which is similar to the pipe 34 connects the duct 29 to the upper end of the 105 well casing, and is provided with a valve 110

38 which is similar to the valve 35, and has an arm 39 connected to the arm 36 of the valve 35 by a rod 40. These valves 35, 38 are arranged reversely, so that when one is 5 in open position, the other is closed. The stem of the valve 38 also has a pair of oppositely extending tappet arms 41, 42 which are, respectively, arranged in the paths of the tappets 32, 33 of the ratchet wheel 31.

10 On one side of the pump is an operating arm 43 which is here shown as pivotally mounted, as at 44, and is oscillated by an eccentric 45 which revolves with and is secured on the shaft 11. The upper end of the 15 operating arm 43 is provided with a suitable pawl 46 for engagement successively with the teeth of the ratchet wheel 31, so that when the pump is in operation the ratchet wheel will be rotated by a step by step movement by the operating arm and its pawl, as 20 will be understood, a second or check pawl 47 being provided to prevent retrograde rotation of the ratchet wheel.

25 The operation of the pump will be as follows. When the piston makes its first cycle and makes its suction stroke air will be drawn from casing 2, and in making its return or compression stroke, the valve 23 will close because air will be forced downwardly into 30 the chamber 22 and the water will pass upwardly through pipe 24, pipe 25 to be discharged. During the next cycle of the piston, when it makes its suction stroke air will be drawn out of chamber 22, so that in 35 making its return or compression stroke the air will be forced into casing 2. Therefore when the piston makes its suction stroke again the air will be drawn from casing 2 and forced into chamber 22 when the piston 40 makes its compression stroke. This operation is repeated again and again as the piston reciprocates, the valve 23 acting always in time. Hence, during the continued operation of the air and compressing piston in 45 the cylinder, compressed air is at one time forced into the well casing and at another time is forced into the receiving pipe, thus causing the receiving pipe to be first filled with water by the action of the compressed

air in the well casing, and then emptied by 50 the action of the compressed air directly in the receiving pipe, and above the column of water therein.

55 While I have herein shown and described a preferred form of my invention, I will have it understood that changes may be made in the form, proportion and construction of the several parts, without departing from the spirit of the invention and within 60 the scope of the appended claims.

What is claimed is:

1. In combination a cylinder, a piston reciprocating therein, means for actuating said piston, a casing connected to said cylinder, a receiving tube disposed concentrically 65 in said casing and projecting below the water level thereof, an upwardly rising valve at the bottom of said tube, a concentric pipe disposed in said receiving tube and terminating short of the bottom thereof, an 70 outlet spout, a pipe connected to said casing and cylinder, a pipe connected to said tube and cylinder, and means for automatically controlling said casing pipe and said tube to produce alternate conditions of suction and 75 pressure therein.

2. In combination a pump casing, a closed cylinder connected thereto, a piston in said cylinder, a receiving tube disposed in said casing, a pipe mounted concentrically in said 80 receiving tube, a risable valve disposed at the bottom of said receiving tube, a pipe connecting the upper end of said casing and said cylinder, a pipe connecting the upper end of said receiving tube and said cylinder, 85 means for causing said first-named pipe to be closed when the other is opened, means acting in time with said piston for controlling said last-named means, a connection between said cylinder and said casing 90 and a discharge spout connected to said first-named pipe.

In testimony whereof I affix my signature in presence of two witnesses.

ALBERT E. JOHNSON.
